UNITED STATES PATENT OFFICE.

HENRY ALLEN AVERY, OTTO PETERMANN, AND EDWIN L. HARMON, OF GROTON, NEW YORK, ASSIGNEES, BY MESNE ASSIGNMENTS, TO L C SMITH & CORONA TYPE-WRITERS INC., OF SYRACUSE, NEW YORK, A CORPORATION OF NEW YORK.

TYPEWRITING MACHINE.

Application filed November 13, 1926. Serial No. 148,258.

This invention relates to improvements in typewriting machines, and more particularly to margin controlling means (including line-locking and line-lock-releasing mechanism) 5 for use in connection with such machines.

The invention has for its principal objects to provide simple and efficient margin stop and margin-stop-releasing devices; to provide a simple and inexpensive margin-alarm 10 and line-locking mechanism; to provide a line-locking means shiftable with a case-shift frame for the platen carriage and adapted to prevent the printing instrumentalities on the main frame of the machine 15 from making impressions; to provide means for blocking printing action by blocking a type-bar-actuated universal bar through the medium of a relatively shiftable dog rocker for the carriage escapement in all case positions of a shift frame upon which the dog 20 rocker is mounted; to provide line-locking means mounted on the shift frame of the machine and releasable from a key in the keyboard; to provide line-locking means adapted 25 to simultaneously lock an escapement mechanism and a releasing mechanism for the escapement against actuation; to provide, in a machine having a dog rocker and a hand-operated escapement releasing device for 30 overthrowing the dog rocker to release the escapement, a line-locking means for locking the dog rocker and also locking said dog-rocker-overthrowing device when the carriage reaches a predetermined letter-space 35 position, and manually operable margin-releasing means for releasing said line-locking means; and to provide line-locking means and releasing means therefor which consists of few parts, is light and compact in 40 construction, and which is adapted to be readily assembled in the machine.

To the foregoing and other ends which will hereinafter appear, the invention consists in the features of constructions, arrangements 45 of devices, and combinations of elements, pointed out in the appended claims, and more fully hereinafter described.

In the drawings, wherein the preferred embodiment of the invention is illustrated, 50 Fig. 1 is a vertical longitudinal sectional view of a portable three-quarter strike typewriting machine containing the improvements, the several parts being in normal position;

Fig. 2 a fragmentary sectional view showing the parts positioned as at the end of a printing stroke of a type bar; 55

Fig. 3 a view similar to Fig. 2 showing the line-locking means in locking position and a type bar restrained from making an impression; 60

Fig. 4 a detail perspective view showing the margin release key in the keyboard fully depressed; 65

Fig. 5 a rear view taken at an angle perpendicular to the plane of shift of the carriage and the plane of the inclined type bar segment, the rear part of the main frame being broken away; 70

Fig. 6 a bottom plan view showing the carriage bed and carriage and parts mounted thereon; 75

Fig. 7 a detail sectional view of the escapement mechanism and adjacent parts of the line-locking and margin-release means; 75

Fig. 8 a detail perspective view showing the stop devices for controlling travel of the carriage toward the right; 80

Fig. 9 a detail perspective view showing the dog-rocker and escapement-releasing means both locked against actuation by the line-locking device; 85

Fig. 10 a fragmentary perspective view of the machine, the several parts being in normal position; and 85

Figs. 11 and 12 sectional views on an enlarged scale showing the manner in which the escapement releasing means blocks locking movement of the line-locking means while said releasing means is in releasing position 90 and until the dog rocker and the escapement releasing bell-crank lever have both returned to normal position. 90

The improvements have been illustrated in connection with a portable three-quarter-strike typewriting machine constructed as disclosed in the applications of Avery, Petermann and Harmon, Serial Nos. 148,255 and 148,257, both filed November 13, 1926. 95

Only so much of said machine as is necessary to a full understanding of the present invention has been shown and will be described. 100

The main frame of the machine comprises a front wall 10, a rear wall 11, side walls 12, and a transverse partition wall 13 lying in an upwardly and rearwardly inclined plane 105 in the rear part of the frame. The type bar

segment 14 is held to the front face of wall 13 by suitable fastening screws with its articulate type-bar-pivot wire 16 lying in a plane parallel with said wall. The type bars 17 are pivoted on wire 16 to strike on the upper front quarter of the platen 18. The character key levers 19 are pivoted at their rear ends on a transverse pivot wire 20 held to a fulcrum plate 21 which is fastened by suitable screws 10 against the rear face of wall 13. Key levers 19 extend down behind wall 13 and then forward under said wall to the keyboard at the forward part of the frame, and are guided in a comb 22 held to the main frame. The 15 connection between each type bar and its associated key lever comprises a bell-crank 23, fulcrumed in a horizontally disposed sublever segment 24 held to the main frame, and links 25 and 26 connecting the bell-crank with the heel of the type bar and the key lever, respectively.

The platen 18 has its shaft 18^a journaled in the end plates of the platen carriage 27 and carrying the usual finger wheels at its ends. 25 Carriage 27 is supported on and travels over the carriage bed 28, the base plate of the carriage and the carriage bed inclining rearward and downward in planes perpendicular to wall 13, and said carriage and bed overlying 30 the space between frame walls 11 and 13. The carriage is supported on front ball bearings 1, confined between raceway members 2 and 3 secured respectively to the carriage base plate and bed, and on a rear roller bearing 4 journaled on a stub shaft 5 held to and projecting rearward and downward from a bar 6 attached to the rear edge of the carriage base plate by screws 7. Roller 4 is located about mid-length of the carriage and travels on a bar 8 held to the rear edge of the carriage bed by screws 9.

A pair of guide members 29 depend from the carriage bed, perpendicular to the plane of the bed, between a pair of guide members 31 attached to the main frame side walls between walls 11 and 13 and extending parallel with wall 13 and guides 29. Guide members 29 are connected by a transverse brace rod 30 at their lower ends and form, with said rod 50 and the carriage bed, a shift frame supporting the carriage to shift in a plane parallel with wall 13 and segment 14, ball bearings 32 being confined in raceways formed in members 29 and 31 parallel with wall 13. The 55 shift frame is shifted through the medium of a torsion frame comprising a rock shaft 36 (journaled on walls 12 adjacent wall 11 and the base line of the main frame) and rock arms 35 held to said shaft and having studs 34 connected with members 29. A shift key lever 33 (fulcrumed on a horizontal pivot screw 38 held to a bracket 39) is connected at its rear end with one of said studs 34 to shift the shift frame. The lower case position of 60 the shift frame is determined by the engage-

ment of stops 41 on the members 29 with stops 42 on brackets 43 attached to frame walls 12. Upper case position of the shift frame is determined by engagement of stops 44 on the members 29 with stops 45 on brackets 43. 70 Bracket 39 is one of a pair of such brackets attached to walls 12 and supporting the type bar rest 40 at its ends.

The foregoing parts are all constructed and arranged as in said applications, above referred to, and as in the well known Corona Four typewriting machine. The escapement for letter-spacing the carriage 27 and the mechanism for operating the escapement, are also constructed as disclosed in said applications. A sheet metal bracket 46 has its flat body part held by screws 47 against the bottom face of carriage bed 28 and extending across an opening 48 in said bed. A steel bushing 49 extends through, and is tightly swaged in, an opening in said body part of the bracket and is formed with a narrow cylindrical hub portion 49^a abutting the said bracket at its upper end, said hub portion being of less diameter than the lower end 90 of the bushing to provide an annular seat 49^b parallel with said body part of the bracket for a line-lock member, hereinafter described, pivoted on said hub.

Bracket 46 is formed with pendent side arms 50 and 51 which extend downward and rearward and carrying at their rear ends the horizontal pivot screws 52 engaged in apertures 53 in pendent pivot ears 54 and 55 formed at the ends of the flat body part of a sheet metal dog rocker 56. A rigid holding dog 57, formed on the forward edge of rocker 56, and a feeding dog 58 (pivoted on the rocker at 59 and controlled by a suitable spring and stop device), cooperate with a toothed escapement wheel 60, to control the feed of the carriage. Wheel 60 is fixed on the lower end of a shaft 61 journaled in bushing 49 and carrying a feed pinion 62 at its upper end meshing with a rack 63. Rack 63 lies between the carriage base plate and carriage bed and is formed integrally with the bar 6 attached to the carriage base plate. The carriage is normally urged toward the left by the usual spring drum 64, held to the carriage bed at 65, and the cable 66, wound on the drum and passing over a pulley 67 (journaled in a slot 68 in the bed) and attached at its free end to a screw 69 secured to the carriage base plate at the right hand end of the carriage. Pinion 62 is adapted to pass through opening 48 in the bed 28, so that bracket 46 together with the parts mounted thereon is removable from and attachable to the bed as a unitary assemblage.

The dog rocker pivot ear 55 is formed with a forwardly extending stop arm 70 formed with an upstanding rearwardly facing hook lug 70^a the upper end of which normally abuts the bottom face of bracket 46 adjacent 130

the inner side of bracket arm 51 to arrest return movement of dog rocker 56 under the pull of the rocker return spring 71. Spring 71 is connected at its rear end with a lug 72 projecting laterally outward from the lower end of rocker pivot ear 54 and is connected at its forward end with a pendent lug 73 on bracket arm 50. The feeding dog 58 normally engages a tooth of the escapement wheel 60 with holding dog 57 above the plane of the wheel. The rocker is provided with an arm 74 depending from its pivot ear 55 and formed with an outwardly extending contact lug 75 at its lower end lying flatwise in a plane perpendicular to wall 13 and the path of movement of the shift frame. The rocker is adapted to be rocked through the medium of said arm 74 and lug 75 to disengage dog 58 and engage dog 57 with escapement wheel 60, by tappets 76 and 77 movable, respectively, with a type-bar-actuated universal bar 78 and a space bar 79 and located forward of lug 75 with their rear lug-contacting edges parallel with the path of shift of the shift frame.

25 The arcuate universal bar 78 lies in a plane parallel with wall 13 and vibrates in a path substantially perpendicular to said wall within a recess 15 formed in the rear face of the type bar segment 14. Said universal bar is supported on the forward ends of a pair of side arms 80 and 81 which extend rearward and downward therefrom, through openings 82 in wall 13 and plate 21, and are provided at their rear inwardly offset ends with guide slots 83 through which shaft 36 extends to support and guide the bars to move endwise substantially perpendicular to wall 13. Said side bars are supported between wall 13 and shaft 36 on rock arms 84 and 85 held to a rock shaft 86 journalled on horizontal pivot screws 87 in arms 88 extending rearward and downward from plate 21 forward of rod 30. The side bars or arms 80 and 81 are connected with the upper ends of rock arms 84 and 85, respectively, by horizontal pivots 89 which swing to opposite sides of a plane through pivots 87 parallel with wall 13.

The tappet 76 is rigid with side arm 81 of the universal bar and, in the machine shown, is normally spaced slightly forward of lug 75. Tappet 77 is rigid with a bar 90 and normally substantially engages lug 75, as shown. Bar 90 is pivotally held at 91 to the lower end of a rock arm 92 depending from a rock shaft 55 93 journalled in ears 94 on comb 22. Said rock shaft is provided with a pair of forwardly extending rock arms 95 to which the space bar 79 is held. Bar 90 extends through a guide slot 96 in comb 22 and then rearward under wall 13. The rear end of said bar lies alongside side arm 81 of the universal bar and is provided with a downwardly inclined guide slot 97 in which engages a stud 98 projecting outward from rock arm 85.

60 65 In the normal operation of the machine the dog rocker is rocked from the position shown in Figs. 1 and 7 to the position shown in Fig. 2 by tappet 76 as a type bar 17 completes its printing stroke, each of said type bars having a lug 17^a which engages the universal bar 78 and pushes it rearward and downward carrying tappet 76 back until it engages against lug 75 and then pushes against said lug to rock the rocker forward and downward until dog 58 is below the wheel 75 60 and dog 57 is engaged with a tooth of said wheel. At this time the type bar engages the platen, and an overthrow-preventing stop 99 on side arm 80 of the universal bar engages shaft 36. At this time, also, a stop lug 100 80 on the dog rocker engages the inwardly bent rear end 101^a of one arm 101 of a bell-crank lever 101—102, pivoted on bracket side arm 51 on a horizontal pivot screw 103, to thereby prevent overthrow of the dog rocker. Lever 85 arm 101 is provided with a rearwardly facing hook lug 101^b alongside the rearwardly facing hook lug 70^a on arm 70 of the dog rocker, said hook lug 101^b being normally held up against the bottom face of bracket 46 by a spring 104 connecting lever 101—102 with bracket arm 51, and said spring being strong enough to hold the rocker against overthrow.

25 30 35 40 45 50 55 60 65 70 75 80 85 90 95 100 105 110 115 120 125 130

Upon depression of the space bar the tappet 77 rocks the dog rocker in the same manner as tappet 76 to letter-space the carriage, overthrow-preventing stops for the space bar (not shown) being provided, constructed and acting in the manner disclosed in said applications.

The universal bar is normally held against the front wall of segment recess 15 by a spring 109 connecting a pendent rock arm 110 on a horizontal shaft 111 (journalled in the main frame) with a spring anchor bar 112 held to said frame, to which bar return springs 113 for the key levers and a return spring 114 for bar 90 and the space bar are also connected. Shaft 111 operates the ribbon mechanism of the machine and is connected with the universal bar by an arm 115 (depending from universal bar side 130

arm 80) and a link 116 connecting arm 115 with a second pendent rock arm 117 on shaft 111.

A margin stop bar 118, of square cross section and having notches 119 in its forward edge, is provided with trunnions 120 at its ends journalled in the end plates of the carriage. A sheet metal rock arm 121 (rigidly held to the right hand end of bar 118) has its forwardly bent lower end 122 normally abutting the rear face of bar 6 on the carriage, said rock arm having a lug 123 below its pivot connected by a return spring 124 for the margin stop bar with a part 125 held to the right hand end plate of the carriage at 126. The margin stop bar is adapted to be rocked by an upstanding release lever 127 rigidly held to the left hand end of said bar, and the throw of the stop bar by 20 said lever is limited by a stop arm 128 extending forward from the lower end of said lever and normally spaced above, and adapted to rock down into engagement with, the base plate of carriage 27.

25 A combined carriage-retaining and stopping plate 129 formed of sheet metal is adjustably held to the carriage bed 28 by screws 130 and 131 passing through the longitudinal slots 132 in a forwardly extending base flange 30 formed on said plate and underlying the bed. Plate 129 extends up behind bars 6 and 8 and is formed with a forwardly extending flange at its upper edge overhanging bar 6, said flange having downwardly bent end lugs 35 133 and 134 in sliding engagement with the upper edge of bar 6 to prevent accidental lifting of the carriage relatively to the bed. The forwardly bent lower end 122 of rock arm 121 on the margin stop bar is adapted 40 to abut the right hand edge of plate 129 to determine the maximum travel of the carriage toward the left. A sheet metal stop member 135, held to the carriage base plate at 136, is provided with a stop lug 135^a projecting rearward over bar 6 and adapted to 45 engage the end of lug 134 on plate 129 to determine the maximum travel of the carriage toward the right.

A pair of adjustable margin stops 137 and 50 138 mounted on stop bar 118 are adapted to arrest travel of the carriage toward the left and toward the right, respectively, at points intermediate the maximum limits of the carriage travel. Each of these stops is provided 55 with a pair of supporting ears slidable along bar 118. Resilient locking members 137^a and 138^a held to stops 137 and 138, respectively, at 137^d and 138^d and urged to the rear by leaf springs 137^b and 138^b, each have locking ears 60 137^c and 138^c through which bar 118 extends, the forward edge of the square opening in which is normally engaged in one of the notches 119 in the margin stop bar. Stop lug 137 is formed with a pendent stop lug 137^e 65 at its lower end adapted to engage and op-

erate a line-locking member, the lower edge of said lug being beveled or inclined downward and toward the left side of the machine.

Stop 138 is formed at its right hand edge 70 with a forwardly projecting stop lug 138^e adapted to engage the straight rearwardly extending left hand side edge of a stop lug 139 punched up from plate 129 and extending rearward from the upper part of said plate flatwise in a plane parallel with the carriage base plate and bed. The right hand side edge of lug 139 is beveled or inclined rearward and toward the left hand side of the machine. 75

The line-locking member operable by margin stop 137 comprises a sheet metal plate 140 having its flat body part underlying bracket 46 and held flat against the bottom face of said bracket by the annular upwardly 80 facing seat or shoulder 49^b on bushing 49, said plate having a slot 141 therein extending rearward from the forward edge of said plate and rounded at its rear end so that the rear end and rear portions of the side walls of 85 the slot hug the periphery of the hub section 49^a of the bushing. Slot 141 thus forms a pivotal bearing aperture in the plate adapted to receive hub 49^a and open at one side so that the plate may be slipped edgewise on and off its pivot. 90

Plate 140 is formed with a rearwardly facing V-shaped notch 142, in its rear end, downwardly into which projects the thick head of the right hand fastening screw 130 for plate 129, said screw head being of less diameter than the width of the notch 142 at the point where said screw head extends into the notch. The left hand wall of notch 142 forms an abutment or stop face normally 105 held engaged with the head of screw 130 by a coil spring 143, with the abutment or stop face formed by the opposite wall of said notch spaced from said screw head. Spring 143 is connected at its rear end with 110 the outer end of an integral arm 144 extending toward the right from the rear end of plate 140 to a point adjacent bracket arm 50, the forward end of the spring being hooked in a notch 145 in bracket arm 50. 115 Spring 143 not only normally holds plate 140 rocked toward the right, but also exerts a constant forward pull on said plate to prevent accidental detachment of the plate from its pivot hub. 120

Arm 144 is offset upward intermediate its ends in rear of plate 129, said upwardly offset part of said arm being formed with a stop lug 146 projecting rearward therefrom and lying flatwise parallel with the carriage base plate and bed. Lug 146 has a straight rearwardly extending right hand edge normally in the path of travel of stop lug 137^e of margin stop 137, and a beveled or inclined left hand edge extending rearward and 125 130

toward the right. Plate 140 is formed with a locking portion or latch arm 147 offset downward from and lying flatwise in a plane parallel with the body part of said plate, said 5 arm normally extending rearward and to the left from the left hand edge of plate 140 and clearing the relatively thin head of fastening screw 131 of plate 129. Arm 147 is normally located in rear of the recesses of 10 the rearwardly facing hook lugs 70^a and 101^b formed on dog rocker arm 70 and escapement releasing bell-crank lever arm 101, respectively, and is adapted to swing into said recesses or hook throats when said plate 140 15 is rocked toward the left until arrested by engagement of the right hand edge of notch 142 with the head of screw 130.

It will be evident that, when the straight left hand edge of stop lug 137^e of margin 20 stop 137 (set on bar 118 at the desired scale point) engages the straight right hand edge of lug 146 on locking member 140, it will swing member 140 toward the left against the pull of spring 143, as the carriage is fed 25 toward the left, until such swinging movement of the locking member 140 is arrested by screw 130, thus causing the arm 147 to engage in the hook lugs 70^a and 101^b. It will be evident that when this occurs the dog 30 rocker is positively locked in normal position so that the carriage cannot be fed farther toward the left. Since the dog rocker cannot tilt, it will be obvious that, if a character key is depressed, its connected type bar 17 35 will simply swing up to the position shown in Fig. 3 where the universal bar 78 has moved slightly rearward and been arrested by tappet 76 striking lug 75 on the locked dog rocker. As the universal bar is thus arrested 40 forward of its normal rearward limit of travel, it blocks the completion of the printing stroke of the type bar and thereby prevents making of superimposed impressions upon the work sheet. It will be apparent, 45 therefore, that the line-locking means locks the universal bar and the type actions against effective operation, and also locks the dog rocker against operation and prevents operation of the escapement release devices. The 50 locking of the escapement releasing bell-crank prevents an operator from exerting injurious strain upon the locked dog rocker in the event the operator should attempt to free the carriage by operating release bail 106.

55 It is frequently desirable to unlock the line-lock in order that one or more letters may be written beyond the marginal line for which stop 137 is set to complete a word or syllable before returning the carriage to begin a new line of writing. This may be done by rocking the stop bar 118 by means of hand lever 127 on said bar, which lever is also operable 60 to rock the bar to permit return of the carriage beyond the point for which margin stop 138 is set when it is desired to write in

the left hand marginal space of the work sheet. It will be obvious that when the stop bar 118 is rocked to carry stop lug 137^e rearward beyond stop lug 146, spring 143 will restore the locking member 140 to unlocked 70 position and stop lug 146 will be carried behind, and to the right of the left hand edge of stop lug 137^e so that the mechanism will not become re-locked upon return of the stop bar 118 to normal position. 75

In order to provide more convenient and speedy means for rocking stop bar 118 for the purpose of unlocking the line-lock, a margin-release key 148 has been provided, located at the right hand side of the keyboard 80 of the machine. Key 148 is supported on the upturned stem portion of the forward arm of a bell-crank release key lever 149. Key lever 149 is pivoted intermediate its ends on a horizontal pivot screw 150 extending transversely of the machine and threaded in the right hand bracket 39 forward of wall 13. A link 151 extends rearward and downward from the upper end of the upturned rear arm of key lever 149 over the right hand end of 90 wall 13 to a point under the carriage bed 28 where it is attached to the outer end of a line-lock-releasing lever 152, the upper edge of wall 13 being cut away at 13^a at its right hand end to afford clearance for link 151. 95 Lever 152 is formed of sheet metal and is pivoted on a screw 153 which passes up through said lever intermediate its ends and is threaded into carriage bed 28. The inwardly extending arm of lever 152 extends 100 rearward to a point beyond the rear face of plate 129 where it is offset upward above arm 144 and is provided with a tappet 152^a at its inner end overlying lug 146 on said arm 144 and normally located forward of the path 105 of stop lug 137^e of margin stop 137.

Release key lever 149 and releasing lever 152 are normally held in the position shown in the drawings by a return spring 154 connected with the rear arm of the key lever at 110 its upper end and connected at its lower end with the anchor bar 112, a stop lug 155 on the key stem of the key lever normally engaging under the key lever stop cushion 156 held to comb 22. Depression of the release key 148 and throw of tappet 152^a is limited by engagement of a stop lug 157, punched laterally from the key-stem, with comb 22, as shown in Fig. 4. It will be evident that, with the parts in locking position, as shown 115 in Fig. 9, depression of the release key 148 will cause tappet 152^a to move rearward and press against the front face of stop lug 137^e of margin stop 137 to swing said margin stop free of the locking member 140 which will 120 snap into normal unlocked position with lug 146 behind lug 137^e.

The beveled left hand edge of lug 146 acts on stop lug 137^e to cam rearward the margin stop 137, when the carriage is returned toward 125 130

the right after completion of the line of writing, following an operation of the line-lock releasing means, so that said margin stop will not obstruct free return movement of the carriage. As the carriage continues its return movement, stop lug 138^e on margin stop 138 comes into engagement with the straight left hand edge of stop lug 139 on plate 129 and arrests the carriage at the left hand 10 marginal point for which stop 138 is set. If it is desired to write within the left hand marginal space, stop 138 may be passed by stop 139 by rocking margin stop bar 118 through the medium of hand lever 127, as 15 hereinbefore described. Upon subsequent advance of the carriage toward the left, lug 138^e will ride over the beveled right hand edge of lug 139 without stopping the carriage, stop 138 swinging rearward as it cams 20 past stop lug 139.

In order that the operator may be warned of the approach of the carriage to the point at which the line-lock will act, an alarm is provided operable by margin stop 137 shortly before said stop actuates the line-locking member. This alarm comprises a bell 158, a bell clapper 159, a spring wire supporting stem 160 for the clapper, and a supporting bracket 161 for the clapper stem. Bracket 161 30 is provided with a forwardly extending lug 162 at its right hand end engaged in a hole in the right hand guide member 29 of the shift frame, which lug together with a fastening screw 163 for bell 158 (passing through the 35 stem of the bell and said bracket) threaded into member 29, holds the bracket to the rear face of member 29. The lower end of the spring stem 160 of the clapper is clamped to the left hand end of bracket 161 by a screw 40 164 threaded into the bracket. Clapper 159 is formed with a rearwardly projecting lug 165 in the path of stop lug 137^e of margin stop 137, which stop lug is adapted to engage lug 165 and flex stem 160 until said stop lug 45 137^e passes over lug 165, whereupon the clapper will whip to the right against the bell before stop 137 actuates the line lock. The beveled lower edge of lug 137^e permits said lug to easily pass the lug on the bell clapper during return movement of the carriage.

It will be obvious that the margin stops are effective in both case positions of the platen; that the line-lock will lock the dog rocker in both case positions of the platen; that the 55 locked dog rocker will prevent an impression being made by the types irrespective of the case position of the shift frame; and that the universal bar, type action, and space bar are rendered ineffective by means which shifts 60 with the shift frame. It will also be observed that the line-locking means mounted on the shift frame is releasable by a key located in the keyboard of the machine. Link 151 is adapted to swing about its point of connection with release key lever 149 during case-

shifting operations, the link being so arranged that its rear moves between two points located substantially equal distances above and below a plane perpendicular to wall 13 and the path of the shift frame and passing 70 through the point of connection of the link with lever 149, so that the key lever 149 will rock releasing lever 152 equally in both case positions of the shift frame.

It is desirable to prevent movement of the line-locking member 140 to locking position in the event of the carriage being run toward the left to the right hand marginal point determined by margin stop 137 with the escapement held released by the manually operable bail 106. The parts are so constructed and arranged, therefore, that upon actuation of the release bail to release the escapement, the line-locking member 140 cannot be actuated by margin stop 137 into locking position until the dog rocker 56 and the bell-crank 101—102 have both returned to normal position following relieving of forward pressure by the operator upon the finger pieces 106^a of the bail, as will be apparent from Figs. 11 and 12 of the drawings.

In Fig. 11 the escapement is shown fully released by a full forward movement of the bail finger pieces 106^a with margin stop 137 pressing against the locking member 140 which has been shifted slightly around its pivot in locking direction but is held against movement into its locking position by reason of engagement of its latch arm 147 with the nose or rear end of hook lug 101^b on the bell-crank 101—102. In Fig. 11 the release bail is shown partly returned to normal position, and it will be observed that the dog rocker has already reached normal position with hook lug 70^a on arm 70 engaged under the bracket 46, the nose of hook lug 101^b at this time still holding the arm 147 of locking member 140 out of locking position and in an ineffective position which has permitted the full return movement of the dog rocker with its arm 70 and hook lug 70^a.

It will be evident that upon completion of return movement of the bail from the position shown in Fig. 12, the parts will assume the locked position shown in Fig. 3, the line-locking member 140 completing its swinging movement under pressure from stop 137 to cause its latch arm 147 to engage in the throats of both hook lugs 70^a and 101^b as the pivoted feeding dog 58 is rocked to carriage-holding position by a tooth of the escapement wheel 60. Possible injury to or jamming of the machine by reason of the line-locking member preventing full return movement of the dog rocker is thus avoided, and locking of the machine against printing is ensured when the marginal point is reached by movement of the carriage to the marginal point by a jump or running movement with the escapement released. It will be apparent from

Figs. 1, 3 and 12 that the inwardly bent end 101^a of bell-crank arm 101, where it crosses arm 70 of the dog rocker, is spaced above said dog rocker arm when lugs 70^a and 101^b are in contact with the bottom face of bracket 46, and that the extent of movement of lug 101^b is such that it will block locking movement of arm 147 of number 140 throughout the movement of arm 70 and hook 70^a from and to normal position during escapement releasing and re-engaging operations.

What we claim is:

1. In a typewriting machine, a traveling platen carriage, escapement mechanism for the carriage, manually operable escapement releasing means, and means operable automatically at a predetermined point in the travel of the carriage under the control of its escapement mechanism for separately locking the escapement mechanism and the escapement releasing means against operation.

2. In a typewriting machine, a traveling platen carriage, escapement mechanism for the carriage, manually operable escapement releasing means, means operable automatically at a predetermined point in the travel of the carriage under the control of its escapement mechanism for separately locking the escapement mechanism and the escapement releasing means against operation, and manually operable means for freeing the escapement mechanism and escapement releasing means from said locking means while the carriage remains stationary.

3. In a typewriting machine, a traveling platen carriage, escapement mechanism for the carriage, manually operable escapement-releasing means normally effective on the escapement mechanism when actuated to free the carriage from control of the escapement mechanism, and line-locking latch operable from the carriage and directly engageable with both the escapement mechanism and said escapement-releasing means to prevent operation thereof.

4. In a typewriting machine, a traveling platen carriage, a margin stop mounted to travel with the carriage and adjustable longitudinally of the carriage, escapement mechanism for the carriage, manually operable escapement-releasing means normally effective on the escapement mechanism when actuated to free the carriage from control of the escapement mechanism, a spring retracted line-locking latch mounted independently of the carriage and operable in opposition to its retracting spring by said stop to directly engage with both the escapement mechanism and said escapement-releasing means to prevent operation thereof, and manually operable margin-release means for unlocking the line-locking latch.

5. In a typewriting machine, a traveling platen carriage, escapement mechanism for

the carriage, key-operated printing means, releasing means for freeing the carriage from control of the escapement mechanism, and line-locking means operable from the carriage to prevent printing operations of said printing means at a predetermined letter-space position of the carriage, said line-locking means including a part co-operating directly with a part of said escapement releasing means when said locking means is actuated to prevent operation of said releasing means.

6. In a typewriting machine, a traveling platen carriage, escapement mechanism for the carriage, key-operated printing means, releasing means for freeing the carriage from control of the escapement mechanism, line-locking means operable from the carriage to prevent printing operations of said printing means at a predetermined letter-space position of the carriage, said line-locking means including a part cooperating directly with a part of said escapement releasing means when said locking means is actuated to prevent operation of said releasing means, and means for unlocking the line-locking means and freeing said releasing means from the restraint of said part.

7. In a typewriting machine, a traveling platen carriage, escapement mechanism for the carriage including a vibratory part operable from the character keys of the machine to effect letter-spacing of the carriage, escapement releasing means adapted to shift said vibratory part to a position in which the carriage is released from control of the escapement mechanism, and line-locking means operable to lock said releasing means against action on said vibratory part and to lock said vibratory part against vibration by the keys.

8. In a typewriting machine, a traveling platen carriage, a margin stop held to travel with the carriage, escapement mechanism for the carriage including a vibratory part operable from the character keys of the machine to effect letter-spacing of the carriage, escapement releasing means adapted to shift said vibratory part to a position in which the carriage is released from control of the escapement mechanism, and a line-locking latch operable by the margin stop to a locking position in which it directly engages both said vibratory part and said releasing means to lock said releasing means against action on said vibratory part and to lock said vibratory part against vibration by the keys.

9. In a typewriting machine, a traveling platen carriage, escapement mechanism for the carriage including a dog rocker pivotally supported independently of the carriage, character-key-operated means for vibrating the rocker to feed the carriage, manually operable escapement releasing means adapted to rock the dog rocker to a point in which the carriage is free from the

control of the escapement mechanism, and line-locking means operable from the carriage and mounted independently thereof, said locking means when actuated to locking position co-operating with the dog rocker to hold the same against vibration by said character-key-operated means and also co-operating with said escapement releasing means to prevent action thereof upon the held dog rocker.

10. In a typewriting machine, a traveling platen carriage, escapement mechanism for the carriage including a dog rocker pivotally supported independently of the carriage, character-key-operated means for vibrating the rocker to feed the carriage, an escapement releasing member pivotally supported independently of the carriage and manually rockable at will to rock the dog rocker to a point in which the carriage is free from the control of the escapement mechanism and a line-locking latch operable from the carriage and mounted independently thereof, said latch when actuated to locking position engaging with the dog rocker to hold the same against vibration by said character-key-operated means and also engaging with said pivoted escapement releasing member to prevent rocking thereof.

11. In a typewriting machine, a traveling platen carriage, a universal bar, printing means actuating the universal bar, escapement mechanism for the carriage including a dog rocker operable from the universal bar, manually operable escapement releasing means for overthrowing said rocker in the direction of its movement by the universal bar to free the carriage from control of the escapement mechanism, and line-locking means operable from the carriage for locking said escapement releasing means against operation on the dog rocker and simultaneously locking the dog rocker to thereby block printing action of the printing means by restraining movement of the universal bar.

12. In a typewriting machine, a traveling platen carriage, an escapement for the carriage including a dog rocker, a type-bar actuated universal bar, a tappet movable positively with the universal bar and arranged for engagement with the dog rocker to rock said rocker during the printing strokes of the type bars, key-operated type bars for actuating the universal bar during their printing strokes, manually operable escapement releasing means engageable with the dog rocker to overthrow the rocker in the direction of its movement by said tappet, and line-locking means operable from the carriage to hold the dog rocker against movement by the tappet and hold said escapement releasing means against action on the held dog rocker.

13. In a typewriting machine, a traveling

platen carriage, an escapement for the carriage including a dog rocker, a type-bar actuated universal bar, a tappet movable positively with the universal bar and arranged for engagement with the dog rocker to rock said rocker during the printing strokes of the type bars, key-operated type bars for actuating the universal bar during their printing strokes, manually operable escapement releasing means engageable with the dog rocker to overthrow the rocker in the direction of its movement by said tappet, line-locking means operable from the carriage to hold the dog rocker against movement by the tappet and hold said escapement releasing means against action on the held dog rocker, and manually operable means for releasing the line-locking means while the carriage remains stationary.

14. In a typewriting machine, a traveling platen carriage, escapement mechanism for the carriage including a key-operated dog rocker supported independently of the carriage, a lever supported independently of the carriage adapted to engage and rock the rocker to a point at which the carriage is free from control of the escapement mechanism, manually operable means on the carriage for rocking said lever at any point in the travel of the carriage, a line-locking member shiftably supported independently of the carriage, means normally urging said locking member in one direction to an ineffective position, and a margin stop traveling with the carriage and adapted to engage and shift said locking member to an effective position in which it is so engaged with both the rocker and said lever as to prevent rocking of the rocker by the keys and prevent rocking of the lever by said manually operable means on the carriage.

15. In a typewriting machine, a traveling platen carriage, escapement mechanism for the carriage including a key-operated dog rocker supported independently of the carriage, a lever supported independently of the carriage adapted to engage and rock the rocker to a point at which the carriage is free from control of the escapement mechanism, manually operable means on the carriage for rocking said lever at any point in the travel of the carriage, a line-rocking member shiftably supported independently of the carriage, means normally urging said locking member in one direction to an ineffective position, a margin stop traveling with the carriage and adapted to engage and shift said locking member to an effective position in which it is so engaged with both the rocker and said lever as to prevent rocking of the rocker by the keys and prevent rocking of the lever by said manually operable means on the carriage, and key-operated margin-release means mounted independently of the carriage and effective on said margin stop when said lock-

ing member is in locking position to shift the stop out of engagement with the locking member.

16. In a typewriting machine, a carriage support, a carriage mounted to travel on said support, a margin stop mounted on the carriage to travel therewith, a swinging line-locking member having a bearing opening therein open at one side to an edge of said member, pivot means on the carriage support extending through the bearing opening in said member and adapted to pass through the open side of the bearing opening, stop means on the carriage support limiting swinging movement of said locking member in opposite directions about said pivot means, and a return spring connected with said member and the carriage support for normally swinging said member in one direction to an ineffective position and constantly urging said member in a direction to prevent lateral separation of the member from its pivot means, said member being engageable and movable by the margin stop about its pivot in opposition to said return spring into machine-locking position.

17. In a typewriting machine, a carriage bed, a platen carriage traveling on the bed, a bracket held to the bed, a bushing held to and extending through the bracket perpendicular to the plane of the bed, a feed pinion shaft journalled in said bushing, a feed pinion on the shaft, a rack on the carriage meshing with the feed pinion, an escapement wheel on the shaft, a dog rocker pivoted on the bracket, dogs on said rocker cooperative with said wheel, said bushing having an annular shoulder spaced below the bracket and an external cylindrical bearing portion be-

tween the bracket and said shoulder, a line-locking member having an open bearing slot in one end through which said external bearing portion of the bushing extends, said slotted end of the locking member being confined between the bracket and said bushing shoulder, a spring connecting said locking member with the bracket to urge the member endwise in a direction to maintain pivotal engagement between the locking member and said external bearing portion of the bushing and to also urge the locking member about its pivot in one direction to ineffective position, stopping means for limiting swinging movements of the locking member in both directions to determine locking and release positions thereof, and a margin stop on the carriage for engaging and swinging the locking member against the action of its spring to locking position.

18. In a typewriting machine, a carriage bed, a platen carriage traveling on the bed, a bracket held to the bed, a bushing held to and extending through the bracket perpendicular to the plane of the bed, a feed pinion shaft journalled in said bushing, a feed

pinion on the shaft, a rack on the carriage meshing with the feed pinion, an escapement wheel on the shaft, a dog rocker pivoted on the bracket, dogs on said rocker cooperative with said wheel, said bushing having an annular shoulder spaced below the bracket and an external cylindrical bearing portion between the said bracket and shoulder, a line-locking member having an open bearing slot in one end through which said external bearing portion of the bushing extends, said slotted end of the locking member being confined between the bracket and said bushing shoulder, a spring connecting said locking member with the bracket to urge the member endwise in a direction to maintain pivotal engagement between the locking member and said bearing portion of the bushing and to also urge the locking member about its pivot in one direction to ineffective position, stopping means for limiting swinging movements of the locking member in both directions to determine locking and release positions thereof, and a margin stop on the carriage for engaging and swinging the locking member against the action of its spring to locking position, said locking member when in locking position having a portion thereof so disposed as to cooperate with a part of the dog rocker to prevent rocking of the dog rocker.

19. In a typewriting machine, a carriage support, a bracket held to the support, a bushing held to said bracket, a shaft journalled in said bushing, a feed pinion and a toothed escapement wheel held to opposite ends of said shaft, a dog rocker pivoted on the bracket, dogs on the rocker cooperative with said wheel, a line-locking member pivoted on said bushing, a spring connecting said member with the bracket and normally holding the member in ineffective position, a traveling carriage on the support, and a margin stop on the carriage adapted to engage and swing said line-locking member into a position in which it obstructs rocking movement of the dog rocker.

20. In a typewriting machine, a traveling platen carriage, a dog rocker pivotally supported independently of the carriage to rock up and down, an upstanding hook-like lug on the dog rocker, a line-locking member pivotally supported independently of the carriage to swing laterally, a margin stop on the carriage engageable with said member to swing the same in one direction to engage a part of said member in said hook-like lug, and a spring connected with said member normally holding the member out of engagement with said lug.

21. In a typewriting machine, a platen carriage, a margin stop on the carriage, a rotary escapement mechanism including a dog rocker and a bearing for a feed pinion shaft, a line-locking member pivotally supported on

said shaft bearing, a spring connected with said locking member and normally holding the same in a release position from which it is movable by the margin stop into a position for obstructing rocking of the dog rocker.

22. In a typewriting machine, a shift frame, a traveling platen carriage on the shift frame, means for shifting the shift frame, escapement mechanism shiftable with the shift frame, escapement releasing means shiftable with the shift frame, normally ineffective locking means for the escapement mechanism and escapement releasing means shiftable with the shift frame, a margin stop on the carriage arranged to actuate said locking means to locking position, printing mechanism on the main frame, and means on the main frame operable by the printing mechanism to actuate the escapement mechanism and adapted to be held by the escapement mechanism in position to prevent printing action of the printing mechanism when said locking means is actuated by the margin stop.

23. In a typewriting machine, a shift frame, a traveling platen carriage on the shift frame, means for shifting the shift frame, escapement mechanism shiftable with the shift frame, escapement releasing means shiftable with the shift frame, normally ineffective locking means for the escapement mechanism and escapement releasing means shiftable with the shift frame, a margin stop on the carriage arranged to actuate said locking means to locking position, printing mechanism on the main frame, means on the main frame operable by the printing mechanism to actuate the escapement mechanism and adapted to be held by the escapement mechanism in position to prevent printing action of the printing mechanism when said locking means is actuated by the margin stop, a margin-release key-lever on the main frame, and means on the shift frame operable by said key lever in all case positions of the shift frame to disengage the margin stop from said locking means.

24. Line-locking means comprising in combination a rotary escapement, and a margin-stop-operated latch for said escapement supported and pivoted on a bearing member for the shaft of the escapement wheel.

25. In a typewriting machine, a toothed feed wheel, a feed pinion, a shaft to which said feed wheel and pinion are held, a bearing member in which said shaft is journaled formed with an external cylindrical bearing portion, a dog rocker, dogs on said rocker cooperating with the feed wheel, a margin-stop-operated latch for the dog rocker pivotally mounted on said external bearing portion of the bearing member for said shaft, and means normally urging said latch out of latching relation with the dog rocker.

26. In a typewriting machine, a traveling carriage, a rack on the carriage, a feed pinion

meshing with the rack, an escapement wheel, a shaft to which said pinion and wheel are held, a bearing member in which said shaft is journaled intermediate the wheel and pinion, a support to which the bearing member is held, said bearing member having an annular shoulder facing said support and an external cylindrical bearing portion between said support and shoulder, a latch pivoted on said external bearing portion and abutting said shoulder and support around its pivotal axis, a dog rocker, dogs on said rocker cooperative with said wheel, a margin stop on the carriage adapted to swing said latch to a latching position in which it holds the dog rocker against rocking movement, and a restoring spring connected with said latch.

27. A typewriting machine as claimed in claim 26, wherein the dog rocker is pivoted on said support and is provided with a hook-like part normally engaged with the support to limit return movements of the dog rocker and in which said latch is engageable to lock the dog rocker in normal returned position.

28. In a typewriting machine, a traveling carriage, an escapement for the carriage including a dog rocker pivotally supported independently of the carriage and having a hook-like stop portion normally engaged with a relatively stationary part of the machine, means connected with the dog rocker for urging the same to normal position, a latch pivotally supported independently of the carriage to swing into and out of the throat of said hook-like part about an axis extending transversely of the pivotal axis of the rocker, means normally urging the latch out of engagement with said hook-like part, and a margin stop on the carriage engageable with said latch to swing the latch into engagement with said hook-like part.

29. In a typewriting machine, a traveling carriage, an escapement for the carriage including a dog rocker pivotally supported independently of the carriage and having a hook-like stop portion normally engaged with a relatively stationary part of the machine, means connected with the dog rocker for urging the same to normal position, a latch pivotally supported independently of the carriage to swing into and out of the throat of said hook-like part about an axis extending transversely of the pivotal axis of the rocker, means normally urging the latch out of engagement with said hook-like part, a margin stop on the carriage engageable with said latch to swing the latch into engagement with said hook-like part, key-operated type bars, and a type-bar-actuated universal bar adapted to rock the dog rocker from normal position during printing strokes of the type bars and held in position to prevent printing action of the type bars through the medium of the dog rocker when the latch is in latching position.

30. In a typewriting machine, a traveling carriage, an escapement for the carriage including a dog rocker pivotally supported independently of the carriage and having a hook-like stop portion normally engaged with a relatively stationary part of the machine, means connected with the dog rocker for urging the same to normal position, a latch pivotally supported independently of the carriage to swing into and out of the throat of said hook-like part about an axis extending transversely of the pivotal axis of the rocker, means normally urging the latch out of engagement with said hook-like part, a margin stop on the carriage engageable with said latch to swing the latch into engagement with said hook-like part, key-operated type bars, a type-bar-actuated universal bar adapted to rock the dog rocker from normal position during printing strokes of the type bars and held in position to prevent printing action of the type bars through the medium of the dog rocker when the latch is in latching position, and key-operated means mounted independently of the carriage for effecting disengagement of the margin stop and latch. 31. In a typewriting machine, a shift frame movable up and down, a platen carriage on the shift frame, a carriage escapement including a dog rocker mounted on the shift frame to swing about a horizontal axis extending transversely of the machine and having a depending operating arm and a stop arm extending forward of its pivot provided with a rearwardly facing recess, a fore and aft vibratable type-bar-actuated universal bar on the main frame, a tappet movable with said bar adapted to push rearwardly on said depending dog rocker arm during printing strokes of the type bars, key-operated type bars on the main frame for moving said universal bar rearward, a return spring for urging the universal bar forward, a return spring for the dog rocker normally forcing said forwardly extending stop arm upward against a fixed part on the shift frame, a latch plate pivotally held to the shift frame at its forward end to swing about an axis perpendicular to the axis of the dog rocker and having a laterally extending left hand latch arm and a second oppositely extending arm, a spring connected with said second latch plate arm to rock the plate toward the right about its pivot, a rockable margin stop bar journalled at its ends on the carriage at the rear of the carriage, a margin stop held to said bar to rock therewith and depending below the said bar, a rearwardly extending lug on said second latch plate arm, a return spring for said stop bar yieldably holding the bar against rocking movement and urging the depending portion of the margin stop forward into a position for engagement with said latch plate lug as the carriage travels toward the left, said latch plate being movable toward the left about its pivot by said margin stop to move its latch arm forward into the recess in said stop arm of the rocker, a lever pivoted on the shift frame and having one end thereof located forward of said lug on the latch plate, and a margin-release key-lever on the main frame connected to rock said lever in all case positions of the shift frame to cause said end of the lever to move rearward against the pendent portion of the margin stop and swing it rearward beyond said lug. 32. In a typewriting machine, a shift frame movable up and down, a platen carriage on the shift frame, a carriage escapement including a dog rocker mounted on the shift frame to swing about a horizontal axis extending transversely of the machine and having a depending operating arm and a stop arm extending forward of its pivot provided with a rearwardly facing recess, a fore and aft vibratable type-bar-actuated universal bar on the main frame, a tappet movable with said bar adapted to push rearwardly on said depending dog rocker arm during printing strokes of the type bars, key-operated type bars on the main frame for moving said universal bar rearward, a return spring for urging the universal bar forward, a return spring for the dog rocker normally forcing said forwardly extending stop arm upward against a fixed part on the shift frame, a latch plate pivotally held to the shift frame at its forward end to swing about an axis perpendicular to the axis of the dog rocker and having a laterally extending left hand latch arm and a second oppositely extending arm, a spring connected with said second latch plate arm to rock the plate toward the right about its pivot, a rockable margin stop bar journalled at its ends on the carriage at the rear of the carriage, a margin stop held to said bar to rock therewith and depending below the said bar, a rearwardly extending lug on said second latch plate arm, a return spring for said stop bar yieldably holding the bar against rocking movement and urging the depending portion of the margin stop forward into a position for engagement with said latch plate lug as the carriage travels toward the left, said latch plate being movable toward the left about its pivot by said margin stop to move its latch arm forward into the recess in said stop arm of the rocker, a lever pivoted on the shift frame and having one end thereof located forward of said lug on the latch plate, and a margin-release key-lever on the main frame connected to rock said lever in all case positions of the shift frame to cause said end of the lever to move rearward against the pendent portion of the margin stop and swing it rearward beyond said lug. 33. In a typewriting machine, a traveling platen carriage, an escapement for the carriage including a dog rocker pivotally supported independently of the carriage, said rocker having a hook formed thereon, a latch pivotally supported independently of the rocker and carriage to swing transversely of the path of movement of the rocker into and out of said hook, a spring connected with said

- latch to urge it toward the right and normally holding the latch out of said hook, a margin stop bar journalled on the carriage, a left-hand margin controlling stop adjustable along said bar, and held to the bar to rock therewith, a spring connected with said bar to yieldably hold the bar in position for engagement of the margin stop with said latch to rock the latch toward the left into said hook, 5 a release key in the keyboard, and a swinging member pivotally supported independently of the carriage and rockable by said key to engage the stop and swing it in unison with the stop bar to which it is held to release the latch.
- 10 34. In a typewriting machine, a traveling platen carriage, an escapement for the carriage including a dog rocker pivotally supported independently of the carriage, said rocker having a hook formed thereon, a latch pivotally supported independently of the rocker and carriage to swing transversely of the path of movement of the rocker into and out of said hook, a spring connected with said latch to urge it toward the right and normally holding the latch out of said hook, a margin stop bar journalled on the carriage, a left-hand margin controlling stop adjustable along said bar and held to the bar to rock therewith, a spring connected with said bar to yieldably hold the bar in position for engagement of the margin stop with said latch to rock the latch toward the left into said hook, a release key in the keyboard, a swinging member pivotally supported independently of the carriage and rockable by said key to engage the stop and swing it in unison with the stop bar to which it is held to release the latch, a right-hand margin controlling stop adjustable along the stop bar and held to rock with the bar, a fixed stop supported independently of the carriage and engageable by the right-hand margin controlling stop to limit the return movement of the carriage, and a hand lever fixed on the stop bar whereby the said bar 20 25 30 35 40 45 50 may be rocked against resistance of its connected spring to permit return movement of carriage beyond the letter-space position for which the right-hand margin controlling stop is set.
35. In a typewriting machine the combination of escapement-releasing mechanism and line-locking mechanism, the line-locking mechanism, when rendered effective, having

a part thereof held in position to block operation of the escapement releasing mechanism. 55

36. In a typewriting machine, the combination of escapement-releasing mechanism and line-locking mechanism, the escapement-releasing mechanism, when rendered effective, having a part thereof held in position to block 60 operation of the line-locking mechanism.

37. In a typewriting machine, the combination of a platen carriage, a dog rocker for the carriage escapement, line-locking means operable automatically to hold the dog rocker in normal position, and manually operable means for rocking the dog rocker from normal position to a carriage releasing position and for preventing a locking movement 65 of the line-locking means while said dog rocker is rocked out of normal position.

38. Line-locking means for typewriting machines comprising in combination, a rotary escapement including a bearing member for the shaft of the escapement wheel, a margin-stop-operated latch for locking the machine having an open-sided pivot bearing slot through which said bearing member extends, and a spring connected with said latch to normally swing the latch about said member to 70 75 80 ineffective position and constantly restrain lateral separation of the latch from said member.

39. In a typewriting machine, an escapement including a bearing sleeve for the escapement wheel shaft, a bracket in the machine through which said sleeve extends and to which said sleeve is held, said sleeve having an annular shoulder spaced from one face of said bracket, a margin-stop-operated latch 85 90 95 for locking the machine having a portion confined between said shoulder and bracket face formed with a pivot-bearing aperture through which said sleeve extends which is open at one side to permit lateral separation of the latch from the sleeve, and a spring connected with said latch to hold the same in pivotal engagement with said sleeve and normally swing the latch about the sleeve to ineffective position. 100

In testimony whereof we hereunto affix our signatures.

HENRY ALLEN AVERY.
OTTO PETERMANN.
EDWIN L. HARMON.
